UNITED STATES PATENT OFFICE.

DAVID H. SMALLEY, OF SOUTH PASADENA, CALIFORNIA, ASSIGNOR OF ONE-HALF TO
EDWARD DOUBLE, OF LOS ANGELES, CALIFORNIA.

APPARATUS FOR PRODUCING POWER.

1,258,713.

Specification of Letters Patent. Patented Mar. 12, 1918.

Application filed August 7, 1916. Serial No. 113,426.

To all whom it may concern:

Be it known that I, DAVID H. SMALLEY, a citizen of the United States, residing at South Pasadena, in the county of Los Angeles and State of California, have invented 5 a new and useful Apparatus for Producing Power, of which the following is a specification.

This invention relates to internal combustion engines and also to the method of producing power from the combustion of liquid fuels.

An object of this invention is to make provision for the utilization of some of the heat units that otherwise would be radiated from the engine and the energy represented thereby lost.

Another object is to maximize the power obtainable from burning a given quantity of fuel oil.

Another object is to effect the foregoing by simple and reliable construction.

Other objects and advantages will appear in the subjoined detail description.

25 The accompanying drawings illustrate two forms of the newly invented apparatus whereby the newly invented method may be performed:

Figure 1 is an elevation mainly in vertical mid section of a one-cylinder four-cycle type of the new apparatus, a portion of the crank case being broken away for clearness of illustration.

Fig. 2 is an end elevation partly in section on line indicated by x^2-x^2 , Fig. 1.

Fig. 3 is an elevation looking at the right hand cylinder head, the piston being in cross section.

Fig. 4 is an elevation mainly in vertical mid section of a two-cylinder two-cycle type of the new apparatus.

Fig. 5 is an elevation, mainly from the irregular line indicated by x^5-x^5 , Fig. 4.

Fig. 6 is a fragmental side-elevation from 45 the left of Fig. 5.

First considering the four-cycle type of the invention shown in Figs. 1 to 3, inclusive, there is provided a cylinder 1 which may be cooled at its combustion end by a water jacket 2 and at its opposite end by heat radiating fins 3. Working in the cylinder 1 is a piston 4 connected by a piston rod 5 and pivot 6 to a pitman 7 which in turn is connected to a crank arm 8 of a crank shaft 9 55 having a fly wheel 10 mounted thereon.

The combustion end of the cylinder is provided with a valve chamber 11 in which are located intake and exhaust valves 12, 13 respectively, said valves being operated at predetermined intervals in a manner well understood in the art by valve gears 14, 15 respectively as shown in Fig. 2 to control intake and exhaust ports 16, 17 respectively of the cylinder.

The foregoing construction corresponds to a known type of Diesel engine and the operation thereof is well understood.

The opposite end of the cylinder 1 is provided with an air tight head 18 having a stuffing box and gland 19, 20 respectively through which the piston rod 5 passes. This end of the cylinder is provided with air intake and exhaust valves 21, 22 which are operated at suitable intervals, as will be more clearly explained hereinafter, by valve gears 23, 24 respectively to control intake and exhaust ports 25, 26 respectively. The valve 21 controls the induction of air through an air induction pipe 25' connected with the intake port 25.

A tube consisting of one or more members as desired, and indicated in general at 26' forms a coil 27 in the combustion end of the cylinder in the compression space *a* behind the piston, and said tube forms another 85 coil 28 in the opposite end of the cylinder in the air compression space *b* in front of the piston. A portion of the tube 26' forms a coil 29 in the air induction tube 25' and another portion forms a coil 30 inside of a 90 water jacket 31. The tube 26' thus forms a closed circuit for a heat conducting medium or agent preferably in the form of mercury 32.

It is well known that, in the operation of 95 internal combustion engines and especially those of the Diesel type, temperature values are relatively great, and it is therefore clear that in practice the engine will be started into operation in a manner well understood 100 in the art to drive the piston on its out-stroke to suck in air through the intake valve 12, to then drive the piston on its in-stroke to compress said air behind the piston 4 in the space *a* and to then force fuel oil 105 through the nozzle 33; whereupon the highly heated compressed air produces ignition of the fuel oil, and combustion thereof then takes place driving the piston 4 on its power out-stroke in the direction of the arrow *c* in 110

Fig. 1. On its return in-stroke the piston 4 scavenges the burnt gases through the exhaust port 17 in a manner well understood in the art. For convenience of description the above described suction, compression, power and exhaust strokes of the piston are herein termed first, second, third and fourth strokes respectively.

The valve gear 23 is so constructed as to 10 open the air intake valve 21 to admit air into the cylinder in front of the piston 4 during said second stroke of the piston utilized for compressing the charge of air in the compression space *a*, and it is clear that 15 when combustion takes place in said compression space *a* some of the heat of combustion will be absorbed by the mercury in the coil 27 so as to vaporize said mercury. The mercury vapor passes along the tube 20 into the coil 28 which transmits said heat to the compressed air space *b*. The air being compressed in the air space *b* by the third stroke of the piston absorbs heat from the coil 28 so that, when the piston 4 starts 25 on its fourth stroke for scavenging the products of combustion from the cylinder, the air thus compressed in the compression space *b* will have a higher degree of expansion force than when said air was being compressed thus materially aiding in propelling the piston 4 on its fourth or scavenging stroke. The air in the compression space *b* expanding tends to cool and extracts more 30 heat from the coil 28 which in turn absorbs heat from the mercury vapor therein.

The mercury vapor circulates through the coil 28 and thence through the coil 29 which in turn radiates heat into the air passing through the air induction tube 25' so as to 40 somewhat cool the mercury vapor and heat the air passing through said tube. From the coil 29 the mercury vapor passes to the coil 30 where said vapor is so thoroughly cooled as to liquefy the mercury, and the liquefied 45 mercury flows from said coil 30 into the coil 27 to be there vaporized again as described above. The piston 4 returning from its scavenging stroke sucks in a new charge of air through the intake port 16 as before 50 and scavenges the expanded air in the compression space *b* through the exhaust port 26, the exhaust valve 22 having been operated to open by its valve gear at the appropriate time in a manner well understood.

From the foregoing it is clear that the mercury circulates from end to end of the cylinder 1 through the tube 26' so as to 55 form a path for the transference of heat from the combustion space *a* to the air compression space *b*. The expanding air in the space *b* is always of greater temperature than the air in said space when said air is being compressed, for the coil 28 and the hot mercury vapor therein are continually 60 imparting heat to said air as it is being com-

pressed, the maximum temperature being reached when the piston 4 is at the extreme end of its out-stroke for compressing said air. Thus it is clear that there is more power derived from the expanding air in 70 the space *b* than is used in compressing said air.

Though the Diesel type of engine has been shown in the drawings and described it is understood that the invention is not limited 75 to the Diesel type but may be embodied in any other type of combustion engine with good results.

The two-cycle type of the invention shown in Figs. 4 to 6 inclusive will now be described: There is provided any desired number of cylinders 34 containing pistons 35 which are connected by piston rods 36, pivots 37 and pitmen 38 to cranks 39 of a crank shaft 40 journaled in bearings 41. 80 There is also provided a two-stage air compressor 42 connected by its piston rod 43 to a crank 44 of the crank shaft 40; and furthermore there is provided a fuel pressure pump 45 connected by its piston rod 90 46 to a crank 47 of the crank shaft.

The cylinders 34 are provided with inlet ports 48 controlled by valves 49 and are also provided with exhaust ports 50 controlled by the pistons 35. The intake valves 49 95 are operated by suitable valve gears 50'.

The construction just described is not uncommon and therefore is readily understood without more detailed description. The cylinders are provided with heads 51, 100 said heads forming boxes 52 and there being glands 53 for the boxes so as to make air tight chambers in front of the pistons 35, the piston rods 36 passing through the stuffing boxes and glands.

There are provided tubes corresponding to the tubes 26' in Fig. 1 and designated by the same reference character and said tubes form coils 27, 28, 29 and 30 just the same as in said figure, the coils 29 being 110 located in air induction pipes corresponding to the air induction pipe 25' shown in said figure and designated by the same reference character, and the coils 30 being enclosed in water jackets 31 as in said figure. 115

The operation of the two-cycle type of engine just described is well understood and taken in connection with the above description of operation of the type of engine shown in Figs. 1 to 3 the functioning of the tubes 120 26' is readily understood as they function in the same manner as the tube 26' in Fig. 1 to circulate the mercury 32 to transmit heat from the combustion ends of the cylinders to the opposite ends to heat the air 125 compressed in front of the pistons. In this instance the expanded air in front of the pistons exhausts through the exhaust ports 50.

Intake valves, intake ports and valve gears 130

for controlling the admission of air to the cylinders in front of the pistons are indicated at 54, 55 and 56 respectively. The term air used in this specification to designate the fluid charge in front of the pistons is understood to define any suitable elastic fluid whether atmospheric gases or other suitable gases.

It is understood that the ports 48 and 10 air induction tube 25' are connected to the air compressor 42, the connections not showing in the drawings on account of the nature of the views, and that the air compressor furnishes air under a predetermined 15 pressure to the cylinders behind and in front of the pistons.

I claim:

1. In combination, a cylinder, a piston in the cylinder, means to introduce a combustible charge into the cylinder behind the piston, means to introduce a charge of air into the cylinder in front of the piston, means to ignite the combustible charge, and means including tubing extending between 25 opposite ends of the cylinder to transmit some of the heat of combustion to the charge of air when said air has been compressed by the piston.

2. In combination, a cylinder, a piston in the cylinder, means to introduce a combustible charge into the cylinder behind the piston, means to introduce a charge of air into the cylinder in front of the piston, means to ignite the combustible charge, pipe 35 coils in both ends respectively of the cylinder in circuit with one another, and a heat conducting medium in the coils.

3. In combination, a cylinder, a piston in the cylinder, means to introduce a combustible charge into the cylinder behind the piston, means to introduce a charge of air into the cylinder in front of the piston, means to ignite the combustible charge, and means to establish a circuit of mercury 45 between the opposite ends of said cylinder.

4. In combination, a cylinder, a piston in the cylinder, means to introduce a com-

bustible charge into the cylinder behind the piston, means to introduce a charge of air into the cylinder in front of the piston, 50 means to ignite the combustible charge, pipe coils in both ends respectively of the cylinder in circuit with one another, and mercury in said coils to transmit heat of combustion to the charge of air.

55

5. In combination, a cylinder, a piston in the cylinder, means to introduce a combustible charge into the cylinder behind the piston, an air intake pipe connected to the cylinder in front of the piston, a valve to 60 control said air intake pipe, means to ignite the combustible charge, and means passing through the air intake pipe to circulate a heat-conducting medium in opposite ends of the cylinder.

65

6. In combination, a cylinder, a piston in the cylinder, means to introduce a combustible charge into the cylinder behind the piston, an air intake pipe connected to the cylinder in front of the piston, a valve to 70 control said air intake pipe, means to ignite the combustible charge, a cooling jacket adjacent the combustion end of the cylinder, and means passing through the air intake pipe and cooling jacket to circulate a heat- 75 conducting medium in opposite ends of the cylinder.

75

7. In combination, a cylinder, a piston in the cylinder, means to introduce a combustible charge into the cylinder behind the piston, means to introduce a charge of elastic fluid into the cylinder in front of the piston, means to ignite the combustible charge, and means to establish a circuit of 80 heat-conducting medium between the opposite ends of said cylinder.

85

In testimony whereof I have hereunto set my hand at Phoenix, Arizona, this 29th day of July, 1916.

DAVID H. SMALLEY.
